UNITED STATES PATENT OFFICE.

EMIL DIETZE, OF BROOKLYN, NEW YORK, ASSIGNOR TO AMERICAN CASTING AND MANUFACTURING CORPORATION, OF BROOKLYN, NEW YORK, A CORPORATION OF NEW YORK.

KEY-LOCK BOX-STRAP FASTENER.

1,348,485.

Specification of Letters Patent.

Patented Aug. 3, 1920.

Application filed August 7, 1918. Serial No. 248,796.

To all whom it may concern:

Be it known that I, EMIL DIETZE, a citizen of the United States, and resident of Brooklyn, in the county of Kings and State 5 of New York, have invented certain new and useful Improvements in Key-Lock Box-Strap Fasteners, of which the following is a specification, reference being had therein to the accompanying drawing.

10 My present invention refers to a box strap fastener which is securely locked in place upon the strap or straps by a keyed locking action, all as will be presently explained, the primary object being to enable a fastening device, which is the equivalent of a seal, to be tightly attached to the strap sections, so that it cannot be detached therefrom. The invention, therefore, consists essentially 15 in the construction, arrangement, and combination of the various parts substantially as will be hereinafter described in the claim.

20 In the accompanying drawing illustrating my invention:

Figure 1 is a perspective view of my improved seal or fastener, shown ready to be attached to two sections of the strap for the purpose of fastening the same together.

25 Fig. 2 is a detail side view of a punch having a special form of movable die for compressing the members of the fastening device and the strap.

30 Fig. 3 is a top plan view showing two strap sections inserted into the fastening device.

35 Fig. 4 is a cross-section of the parts shown in Fig. 3, before the projecting prongs are compressed, the same being taken on the line 5, 5, of Fig. 3.

40 Fig. 5 is a cross-section on the line 5, 5, of Fig. 3 after the projecting prongs have been compressed.

45 Fig. 6 is a longitudinal section on the line 6, 6, of Fig. 3 showing said projecting members compressed to their fullest limit and the material or substance of the straps indented into the openings in the fastening device.

50 Fig. 7 is a bottom plan view of the fastening device after it has been applied to the straps, the latter being shown on the opposite side thereof.

Similar characters of reference designate corresponding parts throughout the different figures of the drawing.

55 1 denotes a plate of metal or similar mate-

rial, preferably of square or rectangular form, with rounded corners, though it may have any size and shape and be made of any material. Near one edge the material of the plate 1 is cut out at a couple of points 2^a to 60 provide a pair of curved lips 2, while on the opposite side the material of the plate 1 is cut out at another pair of points 3^a to furnish another pair of curved lips 3, the pair of lips 3 being, therefore, opposite to the 65 lips 2 and having a space between them sufficient to allow a strap or sections of a strap, as A and B, to be inserted between them, one upon the other for the purpose of securing the said two sections firmly together. 70 Said strap is of the kind that is ordinarily used for fastening a band around a box, bale, or other package, in which case it is essential that the ends of the strap should be closely bound together, and this is done 75 by means of the special fastening device I am now describing. It will be understood that it is not essential to have two pairs of lips or prongs as 2 and 3, but there may be only one lip or prong on each side, or one 80 lip on one side and two or more on the other. The invention is susceptible of a wide variation in these particulars, but of course, as many will be used as are found necessary to make a strong fastener. These lips are pref- 85 erably curved.

The plate 1 with the lips or prongs struck out of the same at points opposite to each other as I have specified is ready to receive the overlying strap sections as A and B, 90 as shown in Fig. 3, and after said sections have been slipped between the prongs I bind these prongs down upon the strap sections by the use of a suitable punch as C having therein a flat die 6 and a movable 95 die 8, the latter being provided with a recess having curved edges at 9 which engage the prongs 2 and 3 and force them down securely upon the strap or strap sections in the manner indicated in Fig. 2.

100 The movable die or jaw 8 causes the compressed prongs 2 and 3 to catch the edges of the strap pieces A and B, as shown in Fig. 4 and press down said edges as shown in Fig. 5, and as the pressure of the prongs 2 and 3 is continued these edges will embed 105 themselves in the openings 2^a and 3^a in plate 1, as shown in Fig. 6. The pressure of the punch will be so great upon the prongs 2 and 3 and will press them so effectively 110

upon the edges of the strap, that said edges will be forced down into the openings 2^a and 3^a and, in fact, through them as shown at points 4 and 5 in Fig. 7, so that said straps at 4 and 5 will be forced practically through the openings 2^a and 3^a so as to lie flush with the bottom surface of the plate 1, or substantially so, being perhaps at times a little less than flush, and at other times, a little more. Thus it will be seen that the parts will be bound very closely and intimately together, and that it will be impossible to dislodge the seal or fastener 1 from the strap sections. The only way that the strap can be removed from the box or bale will be by cutting or breaking it.

The plate 1 is flat and unobstructed from end to end along the space bounded by the projections 4 and 5, so that the strap ends A and B may be inserted endwise between the said projections and lie flat upon the plate.

A fastener of this kind possesses many advantages over others commonly in use, one important advantage being that the strap is not weakened by making openings and breaks therein, for it is kept intact and it is not punctured. Many fastening devices puncture the strap and thereby injure and weaken it, but this device simply compresses the strap at certain points and binds it firmly to the fastening device. Many

changes in the precise form, shape and relative location of various members may be made without exceeding the scope of my invention.

Having thus described my invention, what I claim as new and desire to secure by Letters Patent, is:—

A box strap arrangement, comprising a metal strap with overlapping ends and a seal plate by which the strap ends are secured together, having a substantially flat portion unobstructed by projections on its longitudinal central line, on which portion the strap ends rest, said portion having integral struck-up lips alongside of and in contact with the side edges of the strap ends, and having also openings below the said lips where the latter have been struck out, a portion of the strap ends adjoining and in contact with the aforesaid lips overlying the said openings and adapted to be bent so as to lie in the said openings with the lips in close clamping engagement with the exposed surfaces of the bent portions of the strap ends, and said bent portions occupying the said openings out of which the lips have been taken, substantially as described.

In testimony whereof I hereunto affix my signature.

EMIL DIETZE.
